DOOR HANGER

Frans J. Swart, Rahway, N. J., assignor to Elevator Supplies Company, Inc., Perth Amboy, N. J., a corporation of New Jersey

Application October 23, 1945, Serial No. 624,018

6 Claims. (Cl. 16—97)

1

This invention relates to improvements in door hangers for use with doors of the sliding type.

An object of this invention is to provide an improved and simplified form of door hanger for sliding doors.

Another object of this invention is to provide a door hanger construction especially adapted to ease in assembly, of the type for use with an overhead track in the form of a bar wherein a pair of vertically spaced rollers engage the bar on the upper and lower faces, with the lower rollers adapted for adjusting the play or clearance in a vertical direction between the bar and the cooperating rollers.

Another object of this invention is to provide in a double roller hanger of this type a construction wherein the bearing pin for each roller, one of which is an eccentric pin, is supported at both ends by a construction which facilitates assembly of the structure and especially simplicity in mounting the eccentric pin.

Another object of this invention is to provide a door hanger which will not bind on the hanger rail.

Other and more detailed objects of the invention will be apparent from the following description of the embodiment thereof illustrated in the attached drawings.

This invention resides substantially in the combination, construction, arrangement and relative location of parts, all as will be described in detail below.

In the accompanying drawings,

Figure 1 is a front elevational view of the hanger of this invention;

Figure 2 is a cross-sectional view taken on the lines 2—2 of Figure 1; and

Figure 3 is a side elevational view of the eccentric bearing pin for the lower roller.

The structure as illustrated in the drawings is shown by way of example as comprising a plate 10 of suitable material and thickness, as for example a plate of iron about $\frac{1}{16}$ of an inch thick in one practical form. The upper end of the plate which has converging sides and a truncated end is reversely bent upon itself to form the depending flange 11 spaced from the main body of the plate 10. Journaled in the back portion of the depending flange is a wheel or roller 12 which is rotatably mounted upon a bolt 13 which passes through the rear plate and is threaded engaged at its end in the depending flange 11. Similarly the lower rectangular edge of the plate 10 is reversely bent upon itself to form an upwardly projecting flange 14 likewise

spaced from the back plate. At 15 are indicated certain cutout configurations by means of which the hanger is attached to a cooperating fixture, which in turn is secured to the door. No further reference is made to this feature as it forms no part of this invention.

The upper edge of the flange 14 is defined by a cutout portion comprising two straight converging sides 19 merging with a curved portion 20. An eccentric bearing pin 16 is provided with threads 17 at one end and extends between the rear plate and the flange 14, as is clear from Figure 2. The central portion of the shaft or pin 16 is provided with an eccentric portion 21 of circular cross-section and of a length so as to lie between the back plate and the inner face of the flange 14, as clearly shown in Figure 2. Rotatably mounted on the eccentric portion 21 is a bearing sleeve 22.

In manufacturing this hanger the plate 10 is blanked out in a press so as to have a defining peripheral shape comprising integral triangular and truncated triangular portions, as is clear from the drawings. In the same blanking out operation the openings 15 are cut, as are the two circular holes in the rear wall through which the pins 13 and 16 pass. The flanges 11 and 14 are then formed. The hole to be threaded to receive the front end of the pin 13 and the curved seat

20 with the inclined sides 19 for the flange 14 are then cut by means of punches, which can pass through the two holes in the rear wall previously mentioned, which act as guides or a template for proper alignment of the hole and seat 35 in the flanges 11 and 14 respectively. The hole in the flange 11 is then tapped and then the piece to form the inclined sides 19 is cut out if it was not cut out before the curved seat 20 was formed. This insures proper alignment of the parts.

40 A very practical feature of this invention is concerned with the above stated seat 20 for the front end of the eccentric pin which permits assembly in a simple hanger bracket of the type disclosed, which would otherwise be impossible if the assembly pin were seated at both ends in closed circular seats. In assembling the eccentric pin 16 with the bearing sleeve 22 mounted thereon, the eccentric pin is in a position which is 180° from the position in which the pin is shown 45 in Figure 1, in which case the side of shorter radius can be passed over the notch formed by the inclined side 20 while the threaded end 17 is being inserted in the hole in the rear wall 10. The front end of the pin can then be dropped 50 down into the curved seat 20 and the eccentric

55

pin locked in adjusted rotational position by means of the nut 18.

An advantage of this construction is that after the hangers, of which there are usually two or more for each door, are mounted on the hanger bar so that the hanger wheels 12 ride on its upper edge, the roller sleeve 22 can be adjusted to the proper clearance with the underside of the rail by loosening the nut 18 and rotating the pin 16 in either direction. The eccentric portion 21 as it is rotated will move the sleeve towards and away from the underside of the hanger bar, thus providing the proper clearance between this sleeve and the bar. When properly adjusted it is locked in position by means of the nut 18.

This overall adjustment is of considerable practical importance in view of the fact that if the roller sleeve 18 is at a fixed distance from the hanger wheel 12 an effort must be made to provide just the right clearance with the hanger bar. This is a practical impossibility in view of the fact that the hanger and hanger bar parts vary enough in manufacturing tolerances to result in either too loose or too tight a fit between the hanger and the bar. Thus the structure herein disclosed provides a very inexpensive and effective solution of the problem whereby the hanger can readily be adapted to compensate for all variations in manufacturing tolerances that are likely to occur. In addition it is possible to compensate for wear of the parts as they occur.

From the above description it will be apparent to those skilled in the art that the subject matter of this invention is capable of some variation from the form presented herewith for illustrative purposes. I do not, therefore, desire to be strictly limited to the disclosure as given for purposes of illustration but rather by the claims granted me.

What is claimed is:

1. In a door hanger a supporting plate having one edge reversely bent to form a parallel flange, said plate having an aperture therethrough and said flange having a curved seat in alignment with said aperture and open at the edge of said

flange and an eccentric pin supported in said aperture and on said curved seat.

2. In the combination of claim 1, said eccentric pin having a sleeve rotatably mounted thereon and lying between said plate and flange.

3. A door hanger of the type described comprising a supporting plate having a pair of opposite ends reversely bent to form parallel flanges, a roller lying behind one of said flanges and a pivot pin therefor passing through said plate and adjacent flange, an eccentric pin passing at one end through said plate and resting at its other end on an open sided seat formed at the edge of said flange whereby said eccentric pin is provided with a bearing at each end.

4. A door hanger comprising a supporting plate having an opposite pair of edges reversely bent to form a pair of opposed flanges forming channel ends for said plate, a hanger roller journaled on 20 a pivot pin in one of said channels, a roller sleeve and a removable eccentric pivot pin for supporting said sleeve and being supported at one end in said plate and at the other end in said other flange.

5. In the combination of claim 4 the support in the flange for the eccentric pin being open at the flange edge.

6. In the combination of claim 3, a sleeve rotatably mounted on said pin and lying between 30 said plate and flange.
